UNITED STATES PATENT OFFICE.

GEORGE P. ITTIG, OF BRIDGEPORT, CONNECTICUT, ASSIGNOR TO THE E. H. H. SMITH SILVER COMPANY, OF BRIDGEPORT, CONNECTICUT, A CORPORATION OF CONNECTICUT.

DESIGN FOR A HANDLE FOR SPOONS, FORKS, OR SIMILAR ARTICLES.

41,966.

Specification for Design.

Patented Dec. 12, 1911.

Application filed August 25, 1909. Serial No. 514,656. Term of patent 14 years.

To all whom it may concern:

Be it known that I, GEORGE P. ITTIG, a citizen of the United States, residing at Bridgeport, county of Fairfield, State of Connecticut, have invented a new, original, and ornamental Design for Handles for Spoons, Forks, or Similar Articles, of which the following is a specification, reference being had to the accompanying drawing, forming part thereof.

This invention relates to new and original design for the handle of a spoon, fork, or similar article.

In the accompanying drawing:—Figure 1 is a view of the obverse side. Fig. 2 is a side edge view of the handle. Fig. 3 is a top edge view of the handle. Fig. 4 is a view of the reverse side.

Referring to the drawing, my design consists in convexing the obverse face 10 of the handle and making the reverse face 11 flat

or on a substantially straight line, the two faces being united at their edges by a bead 13 which is approximately circular in cross section. This rib serves as a border extending continuously and unbrokenly around the entire outer edge of the handle. The end of the handle farthest away from the bowl of the spoon is relatively thin as indicated at 14, and is gradually thickened and narrowed as it approaches the bowl, as indicated at 15 the latter point being almost circular in cross section.

What I claim is:—

The ornamental design for a handle for spoons, forks, or similar articles as shown and described.

GEORGE P. ITTIG.
